UNITED STATES PATENT OFFICE

2,438,597

DOOR AND LATCH FOR TUMBLER WASHERS

Charles C. Batina, Chicago, Ill.

Original application October 8, 1941, Serial No. 414,075. Divided and this application August 10, 1942, Serial No. 454,221

2 Claims. (Cl. 68—142)

1

This invention relates to laundry machines and more particularly to washing and drying machines of the rotatable and oscillatory type in which a perforated drum or cylinder containing the laundry to be washed is thoroughly agitated with the washing solution or fluid to thoroughly cleanse the articles being washed and the invention relates more especially to a door construction and latch for such machines or tumbler washers to securely hold the doors in closed position, but permit convenient opening thereof, and is a divisional application of my prior application for Washing machines, Serial No. 414,075, filed October 8, 1941.

Another object of the invention is to provide a novel door and latch construction for laundry machines, especially washing and drying machines or tumbler washers which provides a very rigid structure for the doors and the surrounding edges thereof in connection with the drum or cage thereof so as to provide a maximum of strength to resist the stresses and strains imposed thereon by the pounding of the wet articles of clothes thereagainst during the operation of the machine to resist any tendency to weaken or loosen the parts.

Another object of the invention is to provide a casing or drum construction which will resist stresses due to violent agitation of the clothes and fluid in washing the same and to arrange the door openings thereof with interfitting doors equipped with means to retain the doors rigidly in closed positions while restraining the same against impact and stresses from within or without and at the same time to permit easy and convenient opening thereof for inserting or removing the clothes or preventing the latter from catching or being damaged.

A still further object of the invention is to provide novel sliding or hinged door constructions for the drum, whereby loosening and breaking down of the parts adjacent the door openings is prevented and the same rendered capable of withstanding the stresses and pounding from the agitated washing fluid and laundry therein.

Further objects and advantages will appear and be brought out more fully in the following specification, reference being had to the accompanying drawings, in which:

Fig. 1 is a section taken on the plane of the line 1—1 of Fig. 2.

Fig. 2 is a front elevation of the lower part of the rotating drum of Fig. 1 showing one of the hinged doors, and partly broken away at a latch.

Fig. 3 is an enlarged horizontal section taken

on the line 3—3 of Fig. 2, and showing the hinged door latch construction.

Fig. 4 is an enlarged section of the latch taken on the line 4—4 of Fig. 2.

Fig. 5 is a view similar to Fig. 1, but showing a sliding door instead of a hinged door for the rotating drum.

Fig. 6 is a front elevation similar to Fig. 2 of the drum, as shown in Fig. 5, and with a latch partly broken away.

Fig. 7 is an enlarged fragmentary section of the latch taken on the line 7—7 of Fig. 6.

Fig. 8 is a longitudinal section taken on the line 8—8 of Fig. 6, and

Fig. 9 is a cross-section taken on the line 9—9 of Fig. 7.

Referring to the drawings, the improved laundry machine is illustrated particularly as a washing machine of the rotary or oscillatory type known as a "tumbler" and comprises a stationary cylindrical shell 10 which is imperforate and therefore forms a tank or housing for containing the washing fluid usually composed of hot water and soap solution in which steam is usually injected to assist in the cleansing action. This cylindrical shell is made up of a lower semi-cylindrical section or half and a similar upper section composed of or forming a lateral wall made up of semi-cylindrical or arcuate plates 25 bent on a common concentric arc or circle of the same radius throughout the circumference.

The rotating drum 11 is also cylindrical, but whereas the shell is imperforate, the drum is perforated or reticulated and is made up of a plurality of semi-cylindrical or segmental arcuate sheets or sections 12 forming a lateral wall of slightly smaller diameter than the diameter of the shell 10 and alternating with a plurality of longitudinally extending reenforcing and agitating ribs to be later described. There are preferably five of the ribs and five panels, but four of the sheets or sections 12 extending longitudinally and perforated as shown at 13 in Figs. 1 and 5. These sheets are stamped to provide the perforations and depressed portions or concavities 14 at the inside so that the walls of the perforations are removed from the inner surface of the sheet, thereby providing a smooth surface eliminating all possible corners or projections at the inside

50 which would be likely to catch in the articles being washed. Immediately around the perforations, annular shoulders 15 are formed and at the outside, the depressed portions of the sheet around the cavities are rounded in convex form, 55 as indicated at 16. That is, the metal around the

perforations projects outwardly, and this facilitates the free and unimpeded outward flow of the washing fluid while also permitting the ready entrance thereof through the perforations in that portion of the drum which is immersed in the washing solution contained in the shell. While the perforations are shown staggered or arranged in diagonal rows, it is to be understood that they may be arranged in parallel rows, or otherwise. It will be noted from Figs. 1 and 2 of the drawings that the four panels or sheets 12 are of equal width and extend lengthwise of the drum, but the other panel space is wider and has a narrow upper strip 17 also running longitudinally and a similar lower strip 18 providing door openings 19 at spaced points along the length of the drum. Outwardly turned flanges 20 are provided along the longitudinal edges of the ribs 21 which are substantially V-shaped in cross-section, being relatively arched and projecting radially inwardly. These ribs have inwardly converging flat sides 22 which are perforated as previously described, and an intermediate inner wall 23 which is imperforate. Where the ribs are applied to a drier, as distinguished from a washing machine, the ribs are imperforate at the sides as well as at the inner wall. The flanges 20 are riveted to the strips or sheets 12 in connection with outer end flanges 24 at the corners of angle brackets 25 which are the same shape as the ribs and serve to attach the ribs to the lateral wall as well as to the end walls of the drum and partitions thereof, to be later described. Thus, the flanges of the brackets or hangers are riveted to the walls 22 and 23 of the ribs and also to the end disks or heads 26 of the drum with the ribs extending the entire length of the drum and freely open at the outside between the spaced edges of the sheets or sections 12 and the strips 17 and 18 located in the widest panel of the drum. Flanges 27 are provided on the end disks 26 between the ribs 21 to reinforce and brace the same and flanges 28 are provided on the end caps or heads 29, which are preferably castings. These end caps or heads are provided with spiders or fingers 30, preferably five in number, and in line with the ribs 21. The panel at the door opening 19, as previously stated, is wider than the other panels between the ribs but may be any width, and in order to counterbalance the weight of the door at this longer panel, counterbalancing weights 30a are provided between the spiders 30 at the diametrically opposite side so that the drum will rotate in true balance. At the center, the casting forming the spider 30 produces a hub which is circular and forms a depressed circular flanged disk portion 31 adapted to support trunnions or stud shafts 32 which are of step formation and provided with base flanges 33 to set in the recesses or depressed portions of the hubs or disks 31 and are bolted or otherwise removably secured thereto as at 34. The flanges are also provided with a pair of tapped holes 35 for attaching eye-bolts or the like so that the flanges may be displaced from the recesses and the shafts pulled outwardly to disconnect or displace the same from the ends of the drum so that the latter will be free to be lifted out of the shell when the upper half section thereof is displaced by removing the bolts securing the same. Each trunnion 32 is provided with a roller bearing cage or other similar antifriction bearing.

At the ends of the drum between the door openings 19 and the end disks or heads, flanges

27 are provided, these flanges being narrow and extending circumferentially between the ribs, the same as the sheets or sections 12 of the lateral wall, but need not be perforated. Corresponding strips 37 are secured between the door openings and the strips 36 and 37 are secured in position to the ribs, the same as the sections 12 by means of the brackets 25 and the out-turned flanges of the ribs 21. That is, the brackets have a flange conforming in shape to the shape of a rib and riveted thereto and also having a second flange disposed at right angles to the first flange and riveted to the adjacent end disks or drum heads, as seen more particularly in Figs. 1 and 3. Circular partitions in the form of disks 38 are provided equidistantly between the door openings 19 and opposite edges of the strips 37 and form compartments therebetween and between them and the drum heads. These partitions are secured in position by means of lateral peripheral flanges 39 similar to the flanges 27 and disposed between the ribs, as seen in Figs. 1 and 3. V-shaped cutouts 40 are provided in the partitions 38 at the ribs 21 so that the outer portions of all of the ribs are freely open for the entire length of the drum. To render the structure more rigid, tie rods 41 connect the drum heads or end members and are disposed intermediately of the open outer portions of the ribs, the threaded ends being suitably anchored as by means of nuts 42 on the threaded ends thereof at the outside of the drum heads and for safety, the ends of the rods may be upset against the nuts. Stiffening and reinforcing bands 43 may be provided around the drum to resist the great pressure and stresses imposed thereon and are shown ribbed or beaded outwardly in the center for rigidity, particularly at the partitions 38.

In order to give additional strength to the lateral wall of the drum at the strips 17 and 18 and along the edges thereof at the top and bottom of the door openings, flanged ribs 44 running longitudinally are riveted thereto as also seen in Fig. 1, and the inner flanges thereof may be extended slightly into the door openings to form overlapping portions or seats 45 for the doors to resist inward movement thereof in the manner of shelf extensions. Door seats 46 are also provided between the ribs at the sides of the door openings 19 in conjunction with strips 47 at the outside of the curved side edges of the door openings and keepers 48 are mounted in these strips by riveting the flanged ends thereof to the strips. These keepers may be made with one or both edges beveled as indicated at 49 to facilitate engagement of latch bolts therewith and in either case, are reversible. One type of door 50 is hinged to cooperate with the door openings and provide means for the deposit and withdrawal of articles into and from the drum and are preferably perforated as shown. The doors are hinged by means of a top hinge leaf 51 riveted to the drum wall in conjunction with said reinforcing strips and having leaves 52 riveted to the door with the curled ends or edges of the leaves interfitting and taking one or more pintles or pivot pins 53 to swingingly support the door. Latches 54 are riveted or bolted to the door 50 and the side leaves 52, the casings or housings thereof being flanged at the top and bottom for this purpose and suitably apertured to receive the fastenings. These casings have hollowed out latch pockets 55 with tapered portions 56 forming a recess and flanged seat 57 with an extending V-shaped flange 58 adapted

to receive the ends of a rib 59 at the inside of the door adjacent the bottom or free end thereof and having out-turned flanges at the sides corresponding to the shape of the ribs 21 by means of which the same are riveted to the door to reinforce and strengthen the same. The latch bolt is designated at 60 and operates in the latch pocket 55 at the outside of the casing with a stem 61 passing through the recess 57 and a compression spring 62 encircling the stem between the seats 51 and 60 to normally force the beveled latch end 63 into engagement with the keeper. The latch end is preferably reduced to form shoulders 64 engaging seats 65 at the inside of the casing where the latch end of the bolt projects through and an undercut finger recess 66 is provided in the latch bolt to permit disengagement thereof from the keeper. Openings 67 are also provided in the door and are larger than the finger recesses 66 which set behind the wall of the door, so that the latches may be operated.

The shell 10 may be provided with corresponding hinged doors at the front of the upper section or may be provided with sliding doors, as will now be described. For this purpose, door openings 68 are provided in the shell over the door openings 19 in the drum and the hinged doors 50 in the wall 12 of the upper section of the shell. The lateral wall of the shell at the bottom of the door openings 68 is bent inwardly and downwardly as at 69 to provide an overhanging flange, baffle or deflector for the washing fluid to prevent the same from passing outwardly or splashing on the operator, especially in conjunction with the formation of the bottom edge of the door to be later described. The top edge of the door opening is bent outwardly and upwardly as shown at 70 in the form of a hook to also produce a lock joint or liquid-tight connection with the door, as will be later described. In order to mount the door, spacing strips 71 are riveted or otherwise secured to the lateral wall at the opposite edges of the door opening or to reinforcing strips provided at such points in connection with removable guide strips 72 which project inwardly beyond the spacing strips to form grooves 73 for the door 74 to slide in, in conformity with the periphery of the shell by reason of said parts all being produced on the same arc or radius. The top edge 75 of the door plate is bent inwardly and downwardly or forwardly in hook formation to interfit the hook 70 and form a lock joint which will absolutely prevent the door from dropping down further than a closed position and also the escape of the washing solution from splashing therethrough at such point. The bottom edge of the door is bent inwardly and downwardly or forwardly as at 76 to overlap the bent portion 69 at the bottom edge of the door opening and positively prevent the escape or splashing of the washing solution at the bottom of the door. It is to be understood that water is supplied to the shell or tank in the usual or any preferred way, this usually being hot water with injections of steam through a separate supply source and soap or soap solution or powder for cleansing is supplied through a soap opening 77 in the door over which the soap box 78 is mounted. This box is of triangular cross-section with a straight sloping top edge and has flanged sides bolted or riveted to door at the lateral wall of the shell. A flanged cover 79 is provided for the box and is hinged at the top of the opening 77, preferably with a pintle

having removable cap nuts on the ends thereof for facility and cleaning.

Where sliding doors are provided in lieu of the hinged doors 50 for the drum or shell, the strips 17a and 18a as shown in Fig. 5 corresponding to the strips 17 and 18, may be correspondingly bent. However, the strip 17a is preferably bent outwardly and upwardly or backwardly as at 80 and the top edge of the door 81 is bent inwardly and downwardly or forwardly as at 82, but preferably offset or bent slightly outwardly to pass the offset portions 16 at the perforations in the wall of the drum. The shell doors may be of the same or any preferred construction and strips 83 are provided at the sides and bottom of the door openings 19 and riveted to the strips 17a and 18a at the lateral wall 12, including the bottom edge. Spacers 84 are riveted to the strips 83 and removable strips 85 are provided on the outside to form 20 guide grooves 86 at the sides and overlapping joints at the bottom for the bottom edges of the doors so that when the latter seat in the grooves, extreme rigidity is provided at this point.

The strips 83 are provided with recesses or cutouts 87 to take keepers 88, these keepers being in the form of rectangular sockets, and like the aforesaid keepers 48, being reversible in position. They are provided with top and bottom flanges 89 bolted, riveted or otherwise fastened to the adjacent ends of the strip 83 at the recesses 87. The latches cooperating with each keeper at the opposite sides of the door 74 includes a flanged latch casing or housing 90 bolted or riveted to the wall of the door adjacent the sides and bottom edge and having a pocket 91 opening at the outside with a slot or recess 92 at the inner end thereof forming seats or shoulders at the inside of the pocket on opposite sides of the recess. The inner end is also provided with a V-shaped flange 93 adapted to take the ends of V-shaped ribs 94 corresponding to the ribs 59 and flanged for riveting the same to the door on the inside. The latch bolt body is designated at 95 and has a reduced portion 96 to enter the keeper 88, the reduced engaging portion of the latch bolt being recessed at 97 for this purpose so that the outer face of the bolt will lie flush with the outer face of the keeper. The latch bolt body is also recessed at the outer side or undercut to provide a handle 98 in the form of a hook accessible through a larger opening 98a in the door 81 for releasing the bolt. A pocket 99 is provided on the inside of the latch bolt at the back cooperating with the opposed pocket of the latch housing 55 which has an outwardly projecting lug 100 between which and the outer end of the pocket of the latch bolt, a compression spring 101 is mounted to project the bolt. Shoulders 102 are provided to limit the projection of the bolt through a slot 103 in the casing and the strips 83 are provided with notches 104 at opposite sides to hold the door up, that is, in open position at the opening 19 by engagement of the latch bolts at opposite sides of the door therewith. The bolt is withdrawn by inserting the fingers behind the hook or handle 98 and compressing the spring so that the door may be moved, and in each instance, the engagement of the bolt with the keeper is automatic and assisted by the weight of the door, but may be entirely manually operated.

As before stated, the drum or tumbler 11 is adapted to be rotated within the cylindrical shell or tank 10 in any suitable manner, such as explained in my prior application above referred to.

Should the door openings not be in perfect registration, means may be provided to rotate the drum manually to bring the door openings of the drum in alignment with the door openings of the shell in the different compartments which, in the present instance, are designed to accommodate two hundred pounds of articles of laundry or more, so that the entire capacity is trebled (six hundred pounds) over the ordinary machines, although I do not wish to be limited to this particular capacity. However, it is pointed out that this is possible by reason of the improved and rigid construction and the fact that the longitudinal ribs project inwardly a suitable distance further than any machine constructed and in fact, produce oppositely facing paddles in inwardly converging relation to each other from the periphery of the drum substantially in a plane with the axis of rotation for violently stirring and agitating the washing fluid. The resistance offered to such movement in a washing machine is decreased by the perforations which, due to their peculiar construction, or formation, are prevented from catching in articles of clothing. The ribs upon the interior of the drum also carry the articles around in such a manner that the greatest benefit from the fluid agitation is received and the result is that the articles are thoroughly cleansed, assisted by the periodical reversing of the rotation of the drum by means of the oscillating reversing mechanism, all of which contributes to the thorough cleansing of the laundered articles in the shortest possible time with the least possible consumption of power.

After the deposit of articles to be laundered into the respective compartments of the drum 11 through the aligned door openings of the shell and drum, the desired quantity of water is run or supplied within the shell or tank 10 and passes into the drum and articles to be washed submerged therein. Soap in powder or liquid form is supplied to the hot water through the soap boxes 18 in the shell and the solution passes through the perforations or holes in the walls of the drum and these may be augmented by injections of steam, if desired, to form the required washing solution or fluid. The machine is then operated. The improved construction permits the free circulation of the washing fluid and thoroughly permeates the articles being laundered. The particular formation of the ribs with inwardly converging or outwardly diverging flat sides, instead of being arched or curved, causes more violent agitation of the articles and washing solution by deflecting the same laterally at a lesser angle and besides being rigid to give maximum strength to resist stresses, strains and pounding, increases the flow of the fluid into and out of the drum through the perforate walls thereof and at the freely open outer portions throughout the length of the ribs as well as the surface area, especially as the ribs extend inwardly a greater distance radially, i. e., approximately one-third of the radius of the drum and are balanced to ounces, together with the drum, so that the operation is smooth and uniform. This is also facilitated by locating the tie rods 41 at or near the outer open portions of the ribs and substantially centrally between the perforated sides thereof and by having the bight or intermediate inner transverse portions or walls 23 imperforate so that streams of the washing fluid are alternately forced through one side and then the other as the drum is oscillated or reversely rotated for definite periods of time. However, by having the holes or

perforations punched or stamped out and formed as described with the inner depressions, the free flow, especially outward flow of the fluid, is facilitated while preventing the catching and tearing of the cloth articles.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. In a washing machine, a rotary shell comprising transverse discs, longitudinal ribs extending between said discs forming a plurality of panels, outturned flanges on the longitudinal edges of said ribs, and peripheral flanges on said discs interposed between the edges of the flanges on said ribs, one of said panels being provided with comparatively narrow longitudinally disposed plates connected to the outer faces of the adjacent flanges of the ribs and discs, and transversely disposed plates connected to the disc flanges intermediate said longitudinally disposed plates and together defining a door opening in said shell, perforated plates closing the remaining panels, said longitudinally and transversely disposed plates being in the same cylindrical surface with said perforated plates, longitudinally disposed strips secured to the inner faces of said longitudinally disposed plates between the peripheral flanges on said discs, and curved strips secured to the inner faces of said transversely disposed plates and lying between the adjacent edges of said longitudinally disposed strips, the edges of said longitudinally disposed strips and said curved strips projecting inwardly beyond the edges of the plates to which they are secured forming a door seat, a door hinged to one of said longitudinally disposed plates and adapted to rest on said door seat when closed, and latches on said door adapted to engage under the edges of said strips.
2. In a washing machine, a rotary shell comprising transverse discs, longitudinal ribs extending between said discs, forming a plurality of panels, outturned flanges on the longitudinal edges of said ribs, and peripheral flanges on said discs interposed between the edges of the flanges on said ribs, one of the panels being provided with narrow longitudinally disposed plates connected to the outer faces of the adjacent flanges of the ribs and discs, and transversely disposed plates connected to the disc flanges intermediate said longitudinally disposed plates defining a door opening in said shell, perforated plates closing the remaining panels, said longitudinally and transversely disposed plates being in the same cylindrical surface with said perforated plates, longitudinal strips secured to the inner faces of said longitudinally disposed plates and between the peripheral flanges on said discs, and curved strips secured to the inner faces of said transversely disposed plates between the adjacent edges of said longitudinal strips, the edges of said longitudinal and said curved strips projecting inwardly beyond the edges of the plates to which they are attached forming a door seat, a door hinged to one of said longitudinally disposed plates and adapted to rest on said seat when closed, latches on said door adapted to engage

under the edges of said curved strips, and reenforcing ribs on said longitudinally disposed strips to strengthen the upper and lower plates adjacent the door opening.
